UNITED STATES PATENT OFFICE.

SILAS A. GRITZNER, OF MONTAGUE, MICHIGAN.

VALVE.

1,363,248.

Specification of Letters Patent. Patented Dec. 28, 1920.

Application filed April 25, 1918. Serial No. 230,636.

To all whom it may concern:

Be it known that I, SILAS A. GRITZNER, a citizen of the United States, residing at Montague, in the county of Muskegon and State of Michigan, have invented a certain new and useful Improvement in Valves, of which the following is a specification.

This invention relates to valves and has for its object to provide a new and improved valve, particularly adapted to be used in connection with internal combustion engines. The invention has among other objects to provide a valve which shall be resilient and which cannot be easily warped, and which will snugly fit its seat and will act to keep the valve seat clean. The invention is illustrated in the accompanying drawings, wherein—

Figure 1 is a view of one form of valve embodying the invention;

Fig. 2 is a plan view of the valve shown in Fig. 1;

Fig. 3 is a plan view of the main body of the valve separated from the valve stem;

Fig. 4 is an enlarged sectional view of the valve.

Like parts are indicated by like numerals in all the figures.

Referring now to the drawings I have shown a valve consisting of a body portion made up of a series of laminations. In the construction shown this body portion consists of a series of metal plates 2 and 2^a preferably of steel placed one upon the other as shown. Each of the plates is provided with a series of openings or holes 3 spaced thereabout. The plates 2^a are smaller in diameter than the plates 2 as shown and are preferably arranged so that the outer edge or periphery thereof is inside of the outer edge of the openings 3 thus leaving a series of open spaces 4 at the outer edge of the valve. I prefer to make the two outer plates 5 and 6 without openings and I also prefer to arrange the plates 2 so that there are two or more such plates together and then the plate 2^a and then two or more plates 2 although any other suitable arrangement may be made. By having the outer edge or periphery of each of the plates 2^a fall within the outer edges of the openings 3 it will be seen that these openings 3 then are in communication with the adjacent open spaces 4 as shown in Fig. 4. I also prefer to provide pieces 7 and 8, the plates 2, 2^a, 5 and 6 being between these pieces. These pieces are preferably of aluminum. A valve stem 9 passes through the several pieces as illustrated, and it is provided with a stop 10 on which the piece 7 rests. The other end of the valve stem is riveted or distorted as shown at 11 so as to hold the seven pieces and plates in position.

To facilitate this riveting I may provide the end of the valve stem with an opening 12 which preferably extends nearly part-way therealong, as for example, ending near the top of the valve, the metal surrounding the opening being bent over to produce the clamping effect. The holes 3 in the adjacent plates preferably register and the holes in all of the plates may register if desired although this is not necessary as they would communicate with the spaces 4 whether they registered or not. The edge of the valve seats upon the seat 13 and is preferably beveled or inclined as shown. I also prefer to provide holes 14 and 14 in the top piece 8 for a wrench or turning device in order that the valve may be easily turned to any position desired when in place. Since the valve is made of these comparatively thin metal plates it will be seen that it is resilient, that it readily adjusts itself to the valve seat and that as it is moved back and forth into contact and out of contact with the valve seat it tends to keep the valve seat clean preventing carbon from depositing thereon. It will further be seen that as the valve is brought down on to its seat there is a tendency to compress the plates so as to reduce the area of the spaces 4 and as the valves lift these spaces then they turn to their normal size. This produces a compression expansion of the air or gas in the spaces 4 and holes 3, that is a variation of the pressure therein as the valve opens and closes and this adds to the effectiveness of the construction and assists in keeping the valve seat clean. This construction also prevents warping of the valve and causes it to readily adapt itself to the seat in its normal operation. By providing the holes 3 and the spaces 4 I also make the valve light and the parts 7 and 8 are made of aluminum so as to also decrease the weight of the valve.

I have described in detail a particular construction embodying the invention, but it is of course evident that the parts may be varied without departing from the spirit of the invention as embodied in the claims hereto attached, and I therefore do not limit

the invention to the particular construction shown.

I claim:

1. A valve comprising a body portion made up of a plurality of metal plates of different diameters some of said plates provided with holes, and other of said plates smaller in diameter than the first mentioned plates and interposed between them so as to leave annular spaces at the periphery of the valve.

2. A valve comprising a body portion made up of a plurality of metal plates of different diameters some of said plates provided with holes, and other of said plates smaller in diameter than the first mentioned plates and interposed between them so as to leave annular spaces at the periphery of the valve, the periphery of the plates of smaller diameter falling within the outer edges of the holes and the other plates so that said holes communicate with the adjacent spaces at the periphery of the valve.

3. A valve comprising a body portion made up of a series of metal plates, some of said plates being perforated and other of said plates being imperforate, the imperforate plates smaller in diameter than the perforated plates and arranged intermediate the perforated plates so as to provide annular spaces at the periphery of the valve

and a top and bottom plate between which the other plates are received, said top and bottom plate being imperforate.

4. A valve comprising a body portion made up of a series of metal plates, some of said plates being perforated and other of said plates being imperforate, the imperforate plates smaller in diameter than the perforated plates and arranged intermediate the perforated plates so as to provide annular spaces at the periphery of the valve and a top and bottom plate between which the other plates are received, said top and bottom plate being imperforate, the perforations in the perforated plates being near the periphery of the valve and communicating with the adjacent spaces and the periphery of the said valve.

5. A valve comprising a body portion made up of a plurality of metal plates of different diameters, some of said plates being smaller in diameter than the adjacent plates so as to leave annular spaces at the periphery of the valve.

In testimony whereof, I affix my signature in the presence of two witnesses this 19th day of April, 1918.

SILAS A. GRITZNER.
